ARTICLE OF MANUFACTURE

Frank H. Burke and Ivar O. Moberg, Lowell,
Mass., assignors to Boott Mills, Lowell, Mass.

Application September 10, 1936, Serial No. 100,203

5 Claims. (Cl. 139—387)

This invention relates to an article of manufacture, a window curtain or a window curtain section.

The invention has for its object to provide, in a manner as hereinafter set forth, an article of the type referred to having an integrally woven hem.

A further object of the invention is to provide, in a manner as hereinafter set forth, an article of the type referred to having an integrally woven hem formed with a reinforced outer longitudinal edge.

A further object of the invention is to provide, in a manner as hereinafter set forth, an article of the type referred to having a pair of spaced integrally woven hems with the bends thereof reinforced.

A further object of the invention is to provide, in a manner as hereinafter set forth, an article of the type referred to including a fabric body having a woven hem formed from superposed stretches of the weft threads of the body and with each stretch having interlaced therewith warp threads arranged in parallel pairs.

A further object of the invention is to provide, in a manner as hereinafter set forth, an article of the type referred to including a fabric body formed of an intermediate part and a pair of spaced parallel tubular parts forming lateral continuations of the intermediate part providing woven hems.

A further object of the invention is to provide, in a manner as hereinafter set forth, an article of the class referred to having a woven hem thereby eliminating a lengthwise raw edge and which will launder better than a hem formed by a folded-over portion of the body of the article and with the fold anchored by a row or rows of stitching.

A further object of the invention is to provide, in a manner as hereinafter set forth, an article of the type referred to including hems at its sides free of sewing threads and the puckering of these latter whereby the article will be straighter and hang better.

A further object of the invention is to provide, in a manner as hereinafter set forth, an article of the type referred to with an integrally formed woven hem.

A further object of the invention is to provide, in a manner as hereinafter set forth, an article of the type referred to with an integrally formed woven hem thereby eliminating the use of extra threads and the necessity of removing selvage, as well as overcoming the disadvantages present in

a hem which is sewed on by a sewing machine, as the sewing threads of such type of hem will pucker and have raw edges which will fray.

To the above ends essentially and to others which may hereinafter appear, the invention consists of the novel construction, combination and arrangements of parts as will be more specifically described and are as illustrated in the accompanying drawing wherein is shown an embodiment of the invention, but it is to be understood that changes, variations and modifications may be resorted to which fall within the scope of the invention as claimed.

In the drawing:

Figure 1 is a front elevation of the article of manufacture in accordance with this invention, 15

Figure 2 is a fragmentary view, in plan, broken away and upon an enlarged scale, of the article,

Figure 3 is a fragmentary view in vertical section, broken away and upon an enlarged scale 20 illustrating the outer side hem of the article,

Figure 4 is a section on line 4—4, Figure 2,

Figure 5 is a section on line 5—5, Figure 2, and

Figure 6 is a fragmentary view in perspective and upon an enlarged scale illustrating the inner side hem of the article. 25

The article is formed of an open woven fabric body 1, but it is to be understood that the body 1 may be closely woven, preferably it will be open woven whereby the sides thereof will have 30 a hem-stitched effect.

The body 1 includes an intermediate portion 2, an outer side portion 3, an inner side portion 4, a top portion 5 and a bottom 6.

The body 1 is formed from a single group 7, 35 a pair of superposed groups 8, single groups 9, 10, 11, 12, 13, a pair of superposed groups 14 and a single group 15 of warp threads and said groups interlaced with a weft or filler thread 16. The warp threads of the groups 7 and 15 are of a 40 greater number than the number of threads of the groups 8, 9, 10, 12 and 13. The warp threads of the groups 9, 12 and 13 are of a greater number than the number of threads of the group 10. The number of the threads of the group 11 are 45 materially greater than the number of the threads of any one of the other of said groups. The number of the threads of each of the groups 8 is less than the number of the threads of either of the groups 14. The threads of groups 7 and 15 50 are closely arranged. The threads of the groups 9, 10, 12 and 13 are closely arranged.

The distance between the threads of the groups 8 is greater than the distance between the threads of the groups 7, 9, 10, 12, 13 and 15. The distance 55

between the threads of the group 11 is greater than that between the threads of the groups 7, 9, 10, 12, 13 and 15. The distance between the threads of the groups 14 is greater than that between the threads of the groups 7, 10, 12, 13 and 15. The distance between the threads of the groups 8, 11 and 14 is substantially the same. The group 7 is arranged at one of the longitudinal edges of body 1. The group 15 is arranged at the other longitudinal edge of the body 1. The group 7 is arranged at the outer side and the group 9 at the inner side of the groups 8. The group 10 is arranged at the outer side and the group 12 at the inner side of the group 11. The group 12 is arranged at the inner side and the group 15 at the outer side of the groups 14. The groups 9 and 10 are arranged in parallel spaced relation. The groups 12 and 13 are also arranged in parallel spaced relation.

20 The weft or filler thread 16 extends alternately in opposite directions with respect to the warp threads. The reversal of direction of the weft or filler thread provides bights which constitute the side edges of the curtain. Extending of the weft or filler thread 16 alternately in opposite directions provides it throughout with parallel pairs of oppositely disposed portions termed strands. The strands of each pair are disposed in outwardly and inwardly relation with respect to each other and arranged in superposed relation. The outer strand of each pair of strands of the thread 16 is formed of an elongated intermediate stretch 17, an outer end stretch 19 of less length than and merging at its inner end into one end of the stretch 17 and an inner end stretch 21 of greater length than the stretch 19, and of less length than and merging at its inner end into the other end of the stretch 17. The inner strand of each pair of strands of the thread 16 is formed of an elongated intermediate stretch 18, an outer end stretch 20 of less length than and merging at its inner end into one end of the stretch 18 and an inner end stretch 22 of greater length than the stretch 20 and of less length than and merging at its inner end into the other end of the stretch 18. The stretches 17, 18 are of like length. The stretches 19, 20 are of like length and the stretches 21, 22 are of like length. Bights 23 connect the outer ends of the stretches 19, 20 together and bights 24 connect the outer ends of the stretches 21, 22 together. The stretches 17, 18 are arranged in abutting relation. The stretches 19, 20 are arranged in superposed spaced relation. The stretches 21, 22 are arranged in superposed spaced relation. The groups 9, 10, 11, 12, 13 of the warp threads are interlaced with the stretches 17, 18. One of the groups 8 of the warp threads is interlaced with the stretch 19 and the other group 8 of the warp threads is interlaced with the stretch 20 of the weft threads. One of the groups 14 of the warp threads is interlaced with the stretch 21 and the other group 14 of the warp threads is interlaced with the stretch 22 of the weft threads. The group 1 of the warp threads is interlaced with the stretches 19, 20 and bights 23 of the weft strands. The group 15 of the warp threads is interlaced with the stretches 21, 22 and bights 24 of the weft strands. Those threads of the group 1 which are interlaced with the bights 23 are closely related whereby one lengthwise edge of the curtain is reinforced. Those threads of the group 15 which are interlaced with the bights 24 are

closely related whereby the other lengthwise edge of the curtain is reinforced.

The stretches 19, 20 and bights 23 of the weft strands in connection with the groups 7 and 8 of the warp strands provide an integrally woven tubular hem 25 at the outer side of the body 1 and with the group 7 of the warp threads forming a reinforced outer longitudinal edge for the hem 26.

The stretches 21, 22 and bights 24 of the weft strands in connection with the groups 14 and 15 of the warp threads provide an integrally woven tubular hem 25 at the inner side of the body 1 and with the group 15 of the warp threads forming a reinforced inner longitudinal edge for the hem 26.

As the stretches 19, 20 of the weft strands are of less length than the stretches 21, 22 of such strands the hem 26 is of greater width than the hem 25.

One end terminal portion of the stretches 17, 18 in connection with the group of threads 9 provide for the closing of the inner side of hem 25 without the employment of a stitching. The outer side of hem 25 is closed by the bights 23 and threads 7. The other end terminal portion of the stretches 17, 18 in connection with the group of threads 13 close the inner side of hem 26 without the employment of stitching. The outer side of hem 26 is closed by the bights 24 and the threads 15.

The top and bottom, 5 and 6 respectively of the article are reinforced. The top 5 is formed by folding inwardly one of the end terminal portions of the body 1 and anchoring such end terminal in its folded position. The bottom 6 is formed by folding inwardly the other end terminal portion of body 1 and anchoring such end terminal in its folded position.

The constructing of an article of manufacture 40 such as a curtain or a curtain section in a manner as aforesaid achieves the objects and advantages heretofore set forth.

What we claim is:

1. As a new article of manufacture a window 45 curtain consisting of a fabric body formed of warp threads and a weft thread, said warp threads being divided into a pair of outer groups, a pair of superposed groups inwardly adjacent to one outer group, a pair of superposed groups inwardly adjacent to the other outer group and a set of parallel groups arranged between the said pairs of superposed groups, said weft thread being formed into parallel pairs of superposed strands, the strands of said pairs extending in opposite directions to provide bights at each side of said body, the end terminal portions of the strands being interlaced with the threads of the said pairs of groups and in connection with said bights providing inwardly opening tubular hems 60 at the sides of and coextensive with the length of said body, the threads of the end groups of said set being interlaced with said strands for closing the inner ends of said hems, the groups of said set interlaced with and for maintaining the intermediate portions of the strands between said hems in abutting relation, and the threads of the said outer groups being interlaced with the bights for reinforcing the side edges of said body. 65

2. The invention as set forth in claim 1 having the threads of the said outer groups being arranged in close relation.

3. A curtain comprising a fabric body, said body including a weft thread bent to form par- 75

allel pairs of strands, the strands of said pairs extending in opposite directions to provide bights at the side edges of said body, the strands of each pair being arranged in superposed relation, each strand of each pair being formed of an outer end stretch, an inner end stretch and an intermediate stretch, the outer end stretches of each pair of strands being connected by a bight, the inner end stretches of each pair of strands being connected together by a bight, warp threads common to and interlaced with the end stretches of one strand of each of said pairs, warp threads common to and interlaced with the end stretches of the other strand of each of said pairs, the end stretches of one strand of each pair being spaced from the end stretches of the other strand of each pair, warp threads common to and inter-

laced with the intermediate stretches of the strands of said pairs for maintaining said intermediate stretches in abutting relation, warp threads common to and interlaced with the bights at one side edge of said body for reinforcing such edge, and warp threads common to and interlaced with the bights at the other edge of said body for reinforcing such edge. 5

4. The invention as set forth in claim 3 having the outer end stretches of each pair of strands of less length than the inner end stretches of such pair. 10

5. The invention as set forth in claim 3 having those warp threads interlaced with the bights arranged in abutting relation. 15
